CLAIM

We claim the ornamental design for a data capture device, as shown and described.

DESCRIPTION

FIG. 1 is a top perspective view of an example data capture device;

FIG. 2 is a bottom perspective view thereof;

FIG. 3 is a top view thereof;

FIG. 4 is a bottom view thereof;

FIG. 5 is a first side view thereof;

FIG. 6 is a second side view thereof;

FIG. 7 is a rear view thereof; and,

FIG. 8 is a front view thereof.

Broken lines of a particular embodiment are for purposes of illustrating environment and form no part of the design claimed in that embodiment.

1 Claim, 8 Drawing Sheets

Related U.S. Application Data

a continuation of application No. 29/698,755, filed on Jul. 19, 2019, now Pat. No. Des. 918,914.
